(57) **CLAIM**

The ornamental design for a portable toilet, as shown and described.

DESCRIPTION

FIG. 1 is an isometric view of a first embodiment of the portable toilet;

FIG. 2 is another isometric view of the portable toilet of FIG. 1;

FIG. 3 is a top view of the portable toilet of FIG. 1;

FIG. 4 is a bottom view of the portable toilet of FIG. 1;

FIG. 5 is a rear elevational view of the portable toilet of FIG. 1;

FIG. 6 is a front elevational view of the portable toilet of FIG. 1;

FIG. 7 is a left-side elevational view of the portable toilet of FIG. 1;

FIG. 8 is a right-side elevational view of the portable toilet of FIG. 1;

FIG. 9 is an isometric view of a second embodiment of the portable toilet;

FIG. 10 is another isometric view of the portable toilet of FIG. 9;

FIG. 11 is a top view of the portable toilet of FIG. 9;

FIG. 12 is a bottom view of the portable toilet of FIG. 9;

FIG. 13 is a rear elevational view of the portable toilet of FIG. 9;

FIG. 14 is a front elevational view of the portable toilet of FIG. 9;

FIG. 15 is a left-side elevational view of the portable toilet of FIG. 9; and,

FIG. 16 is a right-side elevational view of the portable toilet of FIG. 9.

The broken line showing of the platform base in FIGS. 1-16 and the broken line showing of the interior toilet fixtures in FIGS. 1, 6, 9 and 14, is included for the purpose of illustrating portions of the portable toilet and forms no part of the claimed design.
